UNITED STATES PATENT OFFICE.

CESARE CARTOTTO, OF WEST NEW YORK, NEW JERSEY.

DESIGN FOR A SPANISH SHAWL.

Application filed September 13, 1928. Serial No. 28,133. Term of patent 3½ years.

To all whom it may concern:

Be it known that I, CESARE CARTOTTO, a citizen of the United States, residing at West New York, in the county of Hudson and State of New Jersey, have invented a new, original, and ornamental Design for Spanish Shawls, of which the following is a specification, reference being had to the accompanying drawing, forming part thereof.

The figure is a plan view of a portion of a Spanish shawl.

I claim:

The ornamental design for a Spanish shawl, as shown.

CESARE CARTOTTO.
